DESIGN FOR A COMBINED ASH TRAY AND COASTER

Patrick Benedict Zazzara, Maplewood, N. J., as-
signor to Jersey Plastic & Die Casting Company,
Newark, N. J., a copartnership

Application December 7, 1948, Serial No. 150,029

Term of patent 7 years

(Cl. D85—2)

To all whom it may concern:

Be it known that I, Patrick B. Zazzara, a citizen of the United States of America and a resident of Maplewood, in the county of Essex and State of New Jersey, have invented a new, original, and ornamental Design for a Combined Ash Tray and Coaster, of which the following is a specification, reference being had to the accompanying drawing, forming a part thereof.

In this drawing:

Figure 1 is a top plan view of a combined ash tray and coaster, showing my new design,

Figure 2 is a side view thereof,

Figure 3 is a right hand end view of Fig. 2; and

Figure 4 is a fragmentary section on the line 4—4 of Figure 1.

I claim:

The ornamental design for a combined ash tray and coaster, as shown.

PATRICK BENEDICT ZAZZARA.
